UNITED STATES PATENT OFFICE.

ARTHUR J. FARMER, OF DETROIT, MICHIGAN.

PAPER FOR USE IN TYPE-WRITTEN WORK TO OBTAIN MANIFOLD COPIES.

No. 878,717.

Specification of Letters Patent.

Patented Feb. 11, 1908.

Application filed May 4, 1904. Serial No. 206,301.

To all whom it may concern:

Be it known that I, ARTHUR J. FARMER, citizen of the United States, residing at Detroit, county of Wayne, State of Michigan, 5 have invented a certain new and useful Improvement in Paper for Use in Type-Written Work to Obtain Manifold Copies; and declare the following to be a full, clear, and exact description of the same, such as will 10 enable others skilled in the art to which it pertains to make and use the same, reference being had to the accompanying drawings, which form a part of this specification.

My invention relates in general to writing 15 paper and more particularly to a sheet of paper for use in making duplicate copies of type-written matter.

It is customary when it is desired to produce duplicate copies of typewritten matter 20 to interpose a sheet of carbon paper between two sheets of blank paper, the three sheets being then inserted between the platen and copying ribbon. The original copy is made on the outer sheet by the type forcing the 25 ribbon against the same, while the second copy is made by the carbon paper upon the inner sheet owing to the impact of the type transmitted through the outer sheet. This method is objectionable as it requires considerable time to arrange by hand the superposed blank sheets and interposed carbon paper and then inserting the series of sheets 30 in the type-writing machine. The handling of the carbon paper soils the hands of the operator and also frequently soils the inner 35 sheet of blank paper when the series of sheets are placed around the platen.

It has been proposed heretofore to obviate 40 the use of carbon paper in making duplicate copies of type-written matter by surrounding the platen of the typewriter with a covering impregnated with coloring matter and providing a roll of a continuous transparent sheet of paper which is moved around the 45 platen coincidently with the movement of separate sheets of paper inserted between the usual ribbon and the continuous sheet of paper. Duplicate copies of the matter written upon the successive separate sheets are 50 impressed upon the continuous sheet from the copying material around the platen. This method is objectionable in that all transparent copies are on a continuous sheet wound around a roller thereby necessitating 55 the continuous sheet being cut into pieces corresponding with the separate sheets on

which the original copies have been made, in order that corrections may be made in the duplicate copies and in order that such duplicate copies may be filed. 60

The primary object of my invention is to provide a sheet of paper upon which duplicate copies of typewritten matter may be made without the use of interposed carbon paper, the two copies being made on superposed portions of the sheet of paper such portions being detachably secured together, thereby permitting corrections to be readily made in both copies and facilitating the filing of one copy owing to its being on a piece of 70 paper of convenient size for handling.

A further object of my invention is to provide a sheet of writing paper upon which duplicate copies of typewritten matter may be made, which will be simple in construction, 75 inexpensive in manufacture, and efficient in use.

My invention generally described consists in a sheet of writing paper comprising two superposed portions detachably secured together, the under portion being transparent 80 so that characters impressed upon the back thereof may be read through the same.

My invention will be more fully described hereinafter with reference to the accompanying drawing in which the same is illustrated as embodied in two convenient and practical forms, and in which,—

Figure 1 is a plan view of a sheet of paper embodying my invention before being folded; Fig. 2 a perspective view of the sheet of paper when folded preparatory to inserting the same in a typewriter, and Fig. 3 a plan view of a modification. 90

Similar reference characters are used to 95 designate similar parts in the several figures of the drawing.

Referring more particularly to Figs. 1 and 2, reference character A indicates one portion of a sheet of paper which may be substantially opaque, translucent, or of any suitable character for receiving impressions from the type of a machine of any usual or ordinary construction. Detachably secured to the portion A is a transparent portion B, the two 100 portions together constituting a sheet of paper adapted to be inserted with the two portions superposed, in a typewriting machine around the platen thereof.

The platen of the typewriter in which my 110 invention is to be used must be provided with a copying material, such for instance as a

ribbon impregnated with pigment or other coloring matter secured around the surface thereof. The sheet of paper is so inserted in the machine that the transparent portion B 5 underlies the portion A and engages the copying surface on the platen.

After the insertion of a sheet of paper embodying my invention the typewriter is operated in the usual manner which results in 10 simultaneous impressions corresponding to the type being made upon both portions of the sheet, one on the portion A due to the type forcing the usual ribbon against the same, and the second copy being produced on 15 the back of the transparent portion B owing to the impact of the type being transmitted through the two portions of paper to the platen.

The two portions of the sheet are detachably secured together so that after the sheet 20 of paper has been removed from the machine the two copies may be separated, the original on the portion A of the sheet for transmission and the duplicate copy on the transparent 25 portion to be filed for record. The two portions of the sheet may be detachably secured together in any suitable way, such for instance as by providing a line of perforations or indentations between the two portions as 30 indicated in Figs. 1 and 2, or by merely securing the two portions together by an adhesive as shown in Fig. 3, reference character A' in such figure indicating the portion of the sheet upon which the original copy is to be

made and reference character B' indicating 35 the transparent portion.

From the foregoing description it will be observed that I have invented an improved sheet of writing paper by means of which 40 duplicate copies of typewritten matter may be produced without the use of carbon paper, both copies being made on pieces of paper of a size convenient for the making of corrections and for filing.

Having now fully described my invention, 45 what I claim as new, and desire to secure by Letters Patent is:

1. An integral sheet of paper consisting of a substantially opaque portion and a transparent portion, said sheet provided with a 50 series of perforations by which the transparent portion may be readily separated from the opaque portion, substantially as described.

2. A doubled, integral sheet of paper, 55 consisting of a substantially opaque portion, and a transparent portion, contacting with each other when folded, said paper provided with a series of perforations along the fold whereby the transparent portion may be readily 60 separated from the opaque portion, substantially as described.

In testimony whereof, I sign this specification in the presence of two witnesses.

ARTHUR J. FARMER.
